UNITED STATES PATENT OFFICE.

WALTER CARL AKANS, OF BIRMINGHAM, ALABAMA, ASSIGNOR OF ONE-HALF TO
J. A. RYAN, OF BIRMINGHAM, ALABAMA.

LOOSE-LEAF BINDER.

1,267,038.

Specification of Letters Patent.

Patented May 21, 1918.

Application filed August 11, 1916. Serial No. 114,430.

To all whom it may concern:

Be it known that I, WALTER CARL AKANS, a citizen of the United States of America, residing at Birmingham, in the county of 5 Jefferson and State of Alabama, have invented certain new and useful Improvements in Loose-Leaf Binders, of which the following is a specification.

My invention relates to loose leaf binders 10 and has for its object to devise a very simple and strong binding means capable of adjustment to bind a substantially lesser or greater number of leaves than that for which the binding is more especially designed. 15 This feature has particular advantage as applied to loose leaf record books, permitting a considerable portion of the leaves to be removed for purposes of being written up or otherwise used and the binding adjusted to 20 tightly and firmly hold the remaining leaves in place. Moreover, if for any reason, it should be desired to incorporate additional leaves in the record book beyond that for which the binder is designed, it can be 25 extended to accommodate these additional leaves. My binder comprises telescopic post sections which are carried by adjustable binding plates relatively movable toward and from each other by means of a trans- 30 versely disposed reversely threaded screw. The adjustment of the binding plates is obtained by mounting them upon a rigid back- 35 ing plate and providing an oblique pin and socket connection between the binding plates and backing plate which causes them to shift both laterally and longitudinally of the backing plate, which is itself riveted or made fast to the back bone. The backing plate is 40 preferably narrower than the back bone and its width corresponds with the normal spacing of the binding plates, which latter how- 45 ever can be adjusted to bring them within or beyond the side edges of the plate, accord- 50 ing to the number of sheets to be bound.

My invention also involves the provision of a simple means of preventing the unauthorized tampering with the book.

My invention also comprises the novel de- 55 tails of construction and arrangements of 60 parts which in their preferred embodiment are illustrated in the accompanying draw- 65 ings, in which:—

Figure 1 is a plan view of the back bone,

backing plate and binding plates in their contracted position.

Fig. 2 shows the binding plates in their maximum expanded position.

Fig. 3 is an enlarged cross sectional view taken on the line 3—3 of Fig. 1, and showing the binding plates adjusted to normal 60 position with the adjusting key in place.

Fig. 4 is a detail view of the key controlled means for the adjusting screw.

Similar reference numerals refer to similar parts throughout the drawings.

As illustrated, I have shown my invention applied to a record book comprising a back bone 1 and side boards 2 suitably hinged thereto. Along the center of the back bone I secure by rivets 3 or otherwise a metallic 70 backing plate 4, which plate stops short of the ends of the back bone and is made substantially narrower in width than the back bone. Mounted upon the backing plate 4 are a pair of adjustable binding plates 5 75 which are formed of sheet metal and comprise each a flat wide base portion 6 and a marginal edge 7 which surrounds all but the inner side edge of each plate. At the center of each plate I rivet or secure an 80 angled bracket 8, which brackets have their upturned ends disposed at the inner edge of each plate and provided with reversely threaded holes to receive the reversely threaded ends of an adjusting screw 10. 85 The leaf binding means comprise posts 11, two of which as shown are made fast to the outer flange of each backing plate and the posts on each backing plate telescope into tubular sleeves 12 on the other backing plate, 90 the length of the sleeve and post being equal to the space between the binding plates when in their most contracted position, *i. e.*, when their edges abut and form a boxlike body as seen in Fig. 1. When the binding plates are 95 expanded to their extreme positions, as seen in Fig. 2, it will be observed that they have shifted both lengthwise and transversely of the backing plate 4. This motion of the binding plates is obtained by the provision 100 in their bases 6 of slots 13, the slots in each plate being inclined in the same direction and the slots in one plate being disposed at right angles to the slots in the other plate. The backing plate 4 carries four rivet pins 105 14 which are passed through the slots 13 and

have wide large heads 15 which engage the top face of the backing plates and hold the latter securely to the base 4 while leaving them free for their diagonal sliding movements relative thereto.

5 The adjustment of the plates is accomplished by turning the screw 10, which serves either to draw the plates together or spread them apart and in such movement 10 the plates are guided by the rivet pins 14. To turn the adjusting screw I provide a key 16 and in a suitable opening provided in one of the flanges 1 insert a key guard or lock 17 which is in line with the unthreaded 15 end 18 of the screw 10. This end 18 is provided with a slot 19 disposed in position to receive the key after the latter has been passed through the guard or lock 17, which is mounted to rotate in the flange so that 20 when the proper key is passed therethrough it can be turned to turn the screw 10 with it.

25 The leaves 20 of the book, which are indicated in dotted lines, Fig. 3, are cut away so as to fit over the binding posts and over 25 the screw 10 and its brackets 8.

30 It will be observed that in the movements of the binding plates lengthwise of the backing leaves they are always protected by the ends of the back bone, and that in their expanded position the outer side edges of the binding plates extend beyond the backing plate 4 to the side edges of the back bone. The rivet pins may be made fast to any suitable back or backing plate and, in fact, any 35 equivalent sliding connection between the binding plates and book may be used which will permit the binding plates to move as described.

Having thus described my invention, 40 what I claim as new and desire to secure by Letters Patent, is:—

1. In a loose leaf binder, a metallic backing plate, binding elements mounted on said backing plate and adjustable lengthwise and 45 transversely thereof, pins connecting said binding elements to the backing plate, there being slots for said pins which are elongated diagonally of the backing plate, and a transverse means for moving said binding members toward and from each other, substantially as described.

50 2. In a loose leaf binder, a back plate carrying studs, binding plates having diagonal elongated slots in which said studs work, oppositely threaded members on said binding plates, and a reversely threaded screw engaging said members and disposed transversely of the plates, substantially as described.

55 3. In combination, a back bone, a narrower and shorter metallic backing plate secured thereto, binding plates mounted on the

backing plate, a slot and pin connection between said binding members and backing plate, the slots being diagonally disposed 65 and the binding plates being movable both transversely and longitudinally of the back bone, alining threaded members near the center of said binding plates, and a transverse reversely threaded screw engaging said 70 members, substantially as described.

4. In a loose leaf binder, a metallic backing plate, binder plates adjustable angularly thereon and movable to positions with their outer side edges contracted between or expanded beyond the side edges of the backing plate, a pin and diagonal slot connection between the backing plates and binding plates, and a transverse reversely threaded screw for moving the plates relatively, substantially as described. 75 80

5. A loose leaf binder comprising, in combination, two binding members formed of plates having a flange surrounding their ends and outer edges, there being reversely 85 inclined diagonal slots in the bases of said plates, a metallic backing plate wider than the combined width of the binding plates and carrying rivet pins which pass through said slots and adjustably secure the binding plates to the backing plate, said slots being elongated to permit the binding plates to spread and bring their side flanges substantially beyond the side edges of the backing plate, and a back bone to which the backing plate is attached, substantially as described. 90 95

6. In a loose leaf binder, two adjustable binding plates having upturned flanges at their outer side edges, telescoping posts carried by said flanges, a back on which said plates are adjustable, pins connecting the binding plates to the back, there being in the plates elongated diagonal slots in which said pins work, and screw means to relatively adjust said binding plates. 100 105

7. In a loose leaf binder, a pair of relatively movable binding plates carrying leaf engaging posts, a back to which said plates are adjustably secured, means to cause the 110 plates to move diagonally across the back as they are adjusted, members on the plates having reversely threaded holes, a reversely threaded screw threaded into said holes, marginal flanges on said plates to receive the 115 back edges of the leaves, a key to turn said screw, and a member, having a key hole, which is rotatably mounted in one of said flanges opposite said screw.

In testimony whereof I affix my signature, 120
WALTER CARL AKANS.
